UNITED STATES PATENT OFFICE.

EARLDLEY C. B. JUDD, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

CLOSET-SEAT FIXTURE.

1,396,934.

Specification of Letters Patent. Patented Nov. 15, 1921.

Application filed February 6, 1920. Serial No. 356,609.

To all whom it may concern:

Be it known that I, EARLDLEY C. B. JUDD, a subject of the King of Great Britain, residing at Chicago, in the county of Cook 5 and State of Illinois, have invented certain new and useful Improvements in Closet-Seat Fixtures, of which the following is a specification.

This invention relates to closet seat fixtures including the seat and the cover and means whereby the hinge members are anchored thereto.

The object of the invention is to provide a strong and substantial seat and cover made 15 of plastic material such as hard rubber having means for securely anchoring the hinge members thereto so that they will not work loose or crack or break the seat or cover.

And a further object of the invention is to 20 reinforce and strengthen the seat and cover by embedding a metal member therein and anchoring the rubber composition to said member throughout its surface to provide a rigid and substantial seat and cover which 25 will withstand the rough usage to which the same may be subjected and which at the same time may be made neat and attractive in appearance and comparatively light in weight. I have selected for illustrating my 30 invention one familiar type of closet seat fixture, but it will be understood that this is illustrative and that the invention may be embodied in any type of seat for which it is or may be adapted.

35 In the drawings—

Figure 1 is a perspective view of the fixture.

Fig. 2 is a top plan view of the cover partly broken away and in section.

40 Fig. 3 is a sectional view on the line 3—3 of Fig. 2.

Fig. 4 is a top plan view of the seat partly broken away and in section.

45 Fig. 5 is a sectional view on the line 5—5 of Fig. 4.

Referring to the drawings, 6 is the cover and 7 is the seat, these parts being made in the general form common in the art and connected by a suitable hinge 8 at their rear 50 ends and mounted at the hinge upon a bowl 9.

The cover and the seat are each composed of a hard rubber composition which is molded and vulcanized upon the perforated

metal reinforce. Referring to Figs. 2 and 55 3, the metal reinforce 10 for the cover extends preferably over the entire area of the cover and where the cover is provided at its sides and front with a depending edge 11 the reinforcing plate is extended down in 60 said edge at 12, being curved substantially in conformity therewith. The plate is provided with openings which may be conveniently made in the form of perforations 13 and distributed throughout the plate so that 65 the composition which embeds the plate may extend through the perforations and homogeneously unite the portions of the composition above and below the plate to form a compact solid cover. At the rear 70 edge of the cover a perforated metal channel 14 is embedded in the depending edge of the cover and is spot welded or otherwise secured to the plate 10. This channel has threaded openings to receive the screw 75 threaded studs 15 of the hinge members 16 and thereby the cover is securely and rigidly fastened to the hinge members. The depending edge 11 preferably extends entirely around the cover and is enlarged at the rear 80 edge of the cover to accommodate the channel. The reinforcing plate and the channel as well as the threaded studs are all wholly embedded in the cover so that it may have a smooth exterior free from corners or 85 crevices.

The seat is preferably made concavo-convex in cross section as shown in Fig. 5, but it may be otherwise constructed if desired. The reinforcing plate 17 in the seat is curved 90 to conform with the concavo-convex curvature of the seat and is preferably like the metal reinforce in the cover and extends throughout the area of the seat. At the rear end of the seat there is an enlarged section 95 18 in which a channel 19 similar to the channel 14 is embedded to receive the threaded studs 20 of the hinge members 21, the construction and arrangement being to all intents and purposes the same as in the cover 100 as previously described. The hinge members 16 and 21 are engaged with a pivot bar 22 suitably mounted on the bowl 9 in a usual manner. The seat and cover are each made of hard rubber composition molded and vulcanized on the perforated metal plates to 105 each form a strong and substantial solid structure. The construction is such that

corners and crevices on the exterior of the seat and cover are entirely avoided and this greatly facilitates maintaining the fixture in a clean and satisfactory condition. My invention provides a seat and cover of the requisite strength and of any desired form and configuration suitable for the purpose which is lighter in weight than solid rubber seats heretofore commercially known. It can be manufactured easily and at a comparatively low cost considering the fact that it will not loosen up in actual use and is practically indestructible. It can be made more attractive and lighter in appearance than the known solid hard rubber fixtures, and because of its lightness it is more easily manipulated.

I prefer to use the perforated metal plate for a reinforce because it is easily shaped and perforated, but I may use other metal reinforcements equivalent thereto and producing substantially the same results. As before stated I do not restrict the use of my invention to the single type of fixture disclosed in the drawings, but reserve the right

to use it in any seat and cover to which it is or may be adapted.

I claim:

1. A closet seat fixture comprising a member composed of hardened plastic material and having a perforated metal channel embedded in the member adjacent the rear edge thereof, and hinge members engaged with said channel. 30

2. A closet seat fixture comprising a member composed of hardened plastic material and having a perforated metal reinforce embedded therein, a perforated metal channel embedded in the member adjacent its rear edge and beneath said reinforce, and hinge members engaged with said channel. 35

3. A closet seat fixture comprising a member composed of hardened plastic material, a perforated metal reinforce embedded in said member, a perforated metal channel imbedded in said member adjacent its rear edge and rigidly secured to the under side 45 of the reinforce, and hinge members engaged with said channel.

EARLDLEY C. B. JUDD.
